UNITED STATES PATENT OFFICE

GEORGE MOSES, OF FISHERS ISLAND, NEW YORK

FOUNTAIN PEN

Application filed June 11, 1929. Serial No. 370,055.

This invention appertains to fountain pens of the self-filling type and has for one of its primary objects the provision of a novel and simple means for insuring the filling of the barrel of the pen, the device being so constructed as to permit a maximum amount of ink to be contained in the barrel.

Another important object of my invention is the provision of positive means for drawing the ink in the barrel, said means embodying a piston sleeve slidably mounted within the barrel and operable upon outward sliding movement thereof in the barrel to draw the ink into the barrel.

15 A further salient object of my invention is the provision of positively locking the sliding piston sleeve in the barrel in its inoperative position against accidental movement while the pen is in use and means for limiting the outward sliding movement of the piston sleeve when the same is being operated to draw the ink into the barrel.

20 A still further object of my invention is to provide novel means for arranging the barrel and the piston sleeve relative to one another so that the leakage of ink between the barrel and sleeve will be precluded and so that a compact structure will be had.

25 A still further object of my invention is to provide a self-filling pen of the above character which will be durable and efficient in use, one that will be simple and easy to manufacture, and one which can be placed upon the market at a reasonable cost.

30 With these and other objects in view, the invention consists in the novel construction, arrangement and formation of parts, as will be hereinafter more specifically described, claimed, and illustrated in the accompanying drawing, in which drawing:

35 Figure 1 is a central longitudinal section through the improved pen showing the same being actuated for drawing the ink within the barrel;

40 Figure 2 is a similar view taken at right angles to Figure 1 and showing the piston sleeve in its inoperative position after the barrel has been filled with ink;

45 Figure 3 is a detail perspective view illus-

trating the novel locking means and guide for the piston sleeve;

50 Figure 4 is an enlarged fragmentary longitudinal sectional view through the improved pen illustrating the novel locking means between the barrel and piston sleeve, the piston sleeve being in its locked position;

55 Figure 5 is a detail transverse section through the barrel and sleeve taken on the line 5—5 of Figure 4 looking in the direction 60 of the arrows;

60 Figure 6 is a detail transverse section taken on the line 6—6 of Figure 4 looking in the direction of the arrows;

65 Figure 7 is an enlarged fragmentary longitudinal section taken at right angles to Figure 4 illustrating the novel locking means employed and showing the piston sleeve in its unlocked position and being withdrawn from the barrel;

70 Figure 8 is a transverse section taken on the line 8—8 of Figure 7 looking in the direction of the arrows, and

75 Figure 9 is an enlarged transverse section taken on the line 9—9 of Figure 1 looking in the direction of the arrows.

80 Referring to the drawings in detail, wherein similar reference characters designate corresponding parts throughout the several views, the letter A generally indicates my improved fountain pen which comprises a barrel 10 open at its rear end and having its forward end contracted for receiving the sleeve plug 11 for the reception of the feeder bar 12 and pen point or nib 13.

85 Slidably mounted within the barrel 10 is a piston sleeve 15 which is closed at its outer end by a suitable head 16 which forms in conjunction with the sleeve a stop shoulder 17 for engaging the outer end of the barrel when the sleeve is in its innermost position, the outer surface of the head being of the same diameter as the outer diameter of the barrel so that the same will be flush with the outer surface of the barrel.

90 From the description so far, it is obvious that when the head 16 is grasped and the piston sleeve pulled outward from the barrel, a suction will be caused in the barrel thereby permitting the drawing of ink into the barrel.

when the pen point and feeder bar are inserted in an ink well.

In conjunction with the barrel 10 and piston sleeve 15, I utilize a novel locking device 20 which forms an important feature of my invention.

The novel locking means 20 includes an axially disposed guide and locking rod 21 having formed or secured to its inner end the anchoring foot 22 which includes resilient arms 23 having laterally extending lugs 24. These lugs 24 are adapted to be sprung into a seating groove 25 formed in the inner surface of the barrel or these lugs 24 can be molded in the barrel. By this arrangement the locking and guide rod 21 is held permanently and axially within the barrel and the rear end of the rod 21 has secured thereto in any desired way a stop head 26 for limiting the outward sliding movement of the piston cylinder as will be later described. The piston sleeve 15 adjacent to its inner end is provided with a diametrically extending locking bar 27 which is provided with a central opening 28 for receiving the guide and locking rod 21 and it is to be noted that the diametrically extending locking bar 27 is confined between the foot 22 and the head 26. The diametrically extending locking bar 27 has the lower face thereof provided with a slot 29 and this slot communicates with a transversely extending cross slot 30 opening out through the opposite sides of the locking bar 27.

35 The guide and locking rod 21 adjacent to its inner end but spaced from the foot 22 is provided with radially extending locking lugs 31 which are of substantially the same size as the slot 29.

40 In operation of the lock, the piston sleeve 15 is moved to its inner most position and the same is turned until the locking lugs 31 aline with the slot 29 and the lugs are pushed into this slot by further inward movement on the piston sleeve. The piston sleeve is now 45 turned so as to bring the locking lugs 31 across the slot 29 and in the cross slot 30. This effectively locks the sleeve and barrel together and holds the sleeve against accidental outward movement. If preferred, the barrel and sleeve can be provided with indicating marks 32 so as to indicate the locked 50 position of the piston sleeve.

55 When it is desired to fill the pen with ink, the pen point or nib is inserted within the ink and the sleeve is turned so as to bring the locking lugs again into alinement with the slot 29 and the piston sleeve is pulled outward, causing the drawing of the ink into the barrel 60 and outward movement of the piston sleeve will be limited by the contacting of the locking bar 27 with the head 26 of the rod 21.

65 The pen is now removed from the ink and the same is held in an upright position thus allowing the escape of air through the feeder

bar and pen point. The piston sleeve is now slowly pushed into the barrel until the same reaches its innermost position at which time the same is again locked in place by bringing the lugs 31 across the slot 29 and into the cross slot 30.

75 While I have disclosed one preferred means of connecting the cross bar 27 with the combined lock and guide rod 27, I can of course use other means such as half threads between the rod and cross bar, but in each instance the piston sleeve is turned a half revolution or 180° to bring about the locking or unlocking of the barrel and sleeve.

80 The pen of course can be equipped with the usual removable cap (not shown).

85 From the foregoing description, it can be seen that I have provided an exceptionally simple and durable pen which can be quickly and easily filled with the maximum amount of ink.

90 Changes in details may be made without departing from the spirit or the scope of this invention.

95 What I claim as new is:

1. A fountain pen of the self-filling type comprising a barrel having a feeder bar and pen point at its forward end and having its rear end open, a piston sleeve slidably mounted within said barrel, an axially disposed guide rod in said barrel, a cross bar carried by the sleeve and slidably mounted on said rod, and means for detachably locking the cross bar to the rod.

100 2. A fountain pen of the self-filling type comprising a barrel open at its rear end and having its forward end closed by a feeder bar and pen point, an axially disposed guide rod in the barrel, means for anchoring the inner end of the rod in the barrel, a piston sleeve slidably mounted in the barrel having a closing head on its outer end for engagement with the outer end of the barrel when the sleeve is in its innermost position in said barrel, a diametrically extending cross bar carried by the sleeve adjacent to the inner end thereof and slidably receiving the guide rod, a head on the outer end of the guide rod limiting the outward movement of the sleeve, and locking means between the bar and rod engageable when the sleeve is in its innermost position in said barrel.

110 3. A fountain pen of the self-filling type comprising a barrel open at its rear end and closed at its forward end by a feeder bar and pen point, a piston sleeve slidably mounted within the barrel, a head of the same diameter as the barrel closing the outer end of the sleeve, an axially disposed guide rod anchored in the barrel, locking lugs carried by the rod adjacent to the inner end thereof, and a diametrically extending lock bar carried by the sleeve adjacent to the inner end thereof and slidably mounted on the rod and having a slot in its lower face communicating with a

cross slot opening out through the opposite faces of the cross bar, the locking lugs being adapted to be received in the cross slot upon the registration of the first slot with said lugs, the barrel being adapted to be turned to an arc of 180° to dispose the lugs in the cross slot at right angles to the first slot, whereby to bring about locking of the sleeve within the barrel.

10 4. A fountain pen of the self-filling type, a barrel having its rear end open and provided with a lock groove on its inner surface adjacent to the inner end thereof, a piston sleeve slidably mounted in the said barrel and having a closing head on its outer end, a guide rod for said sleeve, a cross bar carried by the sleeve adjacent to the inner end thereof slidably mounted on said rod, a foot carried by the inner end of said rod and including a plurality of resilient arms, and radially extending lugs on the terminals of said arms, the lugs being adapted to be sprung into said groove.

20 5. A fountain pen of the self-filling type, a barrel having its rear end open and provided with a lock groove on its inner surface adjacent to the inner end thereof, a piston sleeve slidably mounted in the said barrel and having a closing head on its outer end, a guide rod for said sleeve, a cross bar carried by the sleeve adjacent to the inner end thereof slidably mounted on said rod, a foot carried by the inner end of said rod and including a plurality of resilient arms, radially extending lugs on the terminals of said arms, the lugs being adapted to be sprung into said groove, and means for detachably locking the cross bar to the rod when the piston sleeve is in its innermost position.

40 6. A fountain pen of the self-filling type comprising a barrel, an ink feeding and writing mechanism at the forward end of the barrel, the barrel having its rear end open, a piston sleeve slidably within the barrel, and interlocking members carried respectively by the interior of the piston sleeve and the forward end of the barrel engageable when the piston sleeve is in its extreme forward position in said barrel.

50 7. A fountain pen of the self-filling type comprising a barrel having an ink feeding and writing mechanism at the forward end thereof and having its rear end open, a piston sleeve slidably mounted within said barrel, an axially disposed guide rod in said barrel, a locking device carried by the interior of the piston sleeve for locking engagement with the rod when the piston sleeve is in its extreme forward position, and means on said rod at the rear end thereof for limiting the outward motion of said piston sleeve.

In testimony whereof I affix my signature.
GEORGE MOSES.
